Primary Examiner — Cynthia Ramirez*Assistant Examiner* — Michael A Maharajh*(74) Attorney, Agent, or Firm* — Fitch, Even, Tabin & Flannery LLP(57) **CLAIM**

The ornamental design for a support for disc-like weights, as shown and described.

DESCRIPTION

FIG. 1 is a perspective view of the first embodiment of a support for disc-like weights, showing my new design;
 FIG. 2 is a left side elevation view thereof;
 FIG. 3 is a right side elevation view thereof;
 FIG. 4 is a front elevation view thereof;
 FIG. 5 is a rear elevation view thereof;
 FIG. 6 is a top plan view thereof;
 FIG. 7 is a bottom plan view thereof;
 FIG. 8 is a perspective view of the second embodiment of a support for disc-like weights thereof;
 FIG. 9 is a left side elevation view thereof;
 FIG. 10 is a right side elevation view thereof;
 FIG. 11 is a front elevation view thereof;
 FIG. 12 is a rear elevation view thereof;
 FIG. 13 is a top plan view thereof; and,
 FIG. 14 is a bottom plan view thereof.
 The stippling in FIGS. 8-14 indicates a rough textured surface.
